(57) **CLAIM**

The ornamental design for a bracket cover applied to a
window treatment, as shown and described.

DESCRIPTION

FIG. 1 is a perspective view of a bracket cover applied to a
window treatment showing my new design;

FIG. 2 is a perspective view thereof in an alternate envi-
ronment;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view;

FIG. 9 is a perspective view thereof shown in a different
position;

FIG. 10 is a perspective view thereof in an alternate envi-
ronment;

FIG. 11 is a front view thereof;

FIG. 12 is a rear view thereof;

FIG. 13 is a top view thereof;

FIG. 14 is a bottom view thereof;

FIG. 15 is a left side view thereof; and,

FIG. 16 is a right side view thereof.

The broken lines illustrate structures that form not part of the
claimed design.

The drawings include surface shading which represents
contour and not surface ornamentation.

1 Claim, 8 Drawing Sheets
